SWINGING WRINGER

John B. Castino, River Forest, Ill.

Application August 22, 1934, Serial No. 740,914

4 Claims. (Cl. 68—32)

This invention relates to swinging wringers and more particularly to a wringer of the type manually oscillatable to change the direction of its rotation.

5 An object of the invention is to provide a wringer deriving power and the means of rotation from gears connected with the source of power.

10 A further object is to provide a wringer of the type having gears mounted on a single shaft but whose teeth are inclined oppositely to cause opposite directions of rotation of said wringer.

15 Other and further objects of the invention will appear as the description proceeds, reference being had to the accompanying drawings in which:—

Fig. 1 is a vertical sectional view through the drive shaft and gear of the wringer embodying my invention.

20 Fig. 2 is a side view partly in elevation and partly in cross section.

Fig. 3 is a sectional view taken on line 3—3 of Fig. 2.

25 Fig. 4 is a view similar to Fig. 1 showing the modified construction.

Like reference characters refer to like parts in the several figures.

Referring more particularly to the drawings, reference character 10 represents a horizontal shaft connected to a source of power, and held in the bearing 11 which is supported in casing 12. The shaft 10 has at its end 13 the miter gear 14 which engages the two horizontal miter gears 15 and 16. The gear 16 is affixed to shaft 17 and the gear 15 is affixed to the tubular shaft 18. The pair of gears 19 and 20 are affixed at the upper ends of shaft 17 and 18 respectively. Wringer rolls 21 and 22 have mounted thereon at one end or at the end adjacent and engaged 40 with the gears 19 and 20, the gears 23 and 24. The wringer rolls 21 and 22 are pivotally held in an inverted U shaped frame 25 which in turn is pivotally mounted on the pintles 26 and 27 which are held fixedly in the end frames 28 and 45 29. These frames are connected by the spacers 29A with nuts 29B. The end frame 28 has an integral housing 30 for the gears 21 and 22. The handle member 31 is pivoted on pintles 32 and 33, and is yieldably held by the two expansion coiled 50 springs 34. The yoke 35 underneath handle member 31 engages the pin 36 on the U shaped frame 25.

The drain board 37 pivoted at 38 is moved by a pin 39 on the frame 25 which engages in the 55 U slot 40 on the frame 41 of the drain board 37.

The guards 42 and 43 are pivoted at 44 and 45 respectively on frame 25 and have the integral gears 46 and 47 which engage each other. The coil tension spring 48 tends to hold the guards 42 and 43 in proximity to the lower roll 22; contact with said roll being prevented by the detents 49 and 50.

5 The modification shown in Fig. 4 of the drawings provides a single vertical shaft 17 on which are fixed the two gears 19 and 20. The teeth 19A of gear 19 are inclined in the same direction as the teeth 20A of gear 20.

10 Wringer gears 23 and 24 are spiral and inclined in a like direction. It will be readily understood that the rotation direction of the wringer rolls 15 will depend on whether or not the gear 19 or 20 is engaged therewith.

15 In operation, the source of power driving the shaft 10 will rotate gear 14 in engagement with miter gears 15 and 16 which accordingly will turn in opposite directions, thus imparting opposite direction of rotation of the shaft 17 and 18 causing gears 19 and 20 to turn in opposite directions. Manipulation of the handle member 31 will bring either one of gears 23 or 24 into contact with its 20 associated gear 19 or 20 causing the connecting 25 wringer roll to turn in conjunction with the driving gear contacted. The same operation will tilt the drain board 37 holding it in the same direction in which the handle member 31 is held.

30 The guard 43 as shown in Fig. 3 has a laterally extending handle portion 51 which the operator may grasp and pull outward the guards 42 and 43, whereupon the cloth may be placed over the point 52 and set guard 43 to action and the 35 springs 48 will automatically return the guards to the position adjacent to the wringer thus causing the cloth to be drawn toward the rolls.

Having thus described my invention, what I claim and desire to secure by Letters Patent of 40 the United States, is:—

1. In a wringer of the class described, a power shaft, a gear thereon, a tubular shaft, a rod shaft therein, gears on the tubular shaft and the rod shaft in mesh with the power shaft gear, a pair 45 of wringer rolls mounted to oscillate about an intermediate axis parallel thereto, gears on said rolls, and gears on said tubular shaft and said rod shaft alternately engagable with the gears on said wringer rolls by oscillation of said pair 50 of wringer rolls as a unit.

2. In a wringer, a vertical tubular shaft connected to a source of power, a rod shaft there within connected with said source of power to rotate oppositely to the tubular shaft, gears on 55

the heads of said shafts and a pair of wringer rolls pivoted to swing radially about said shafts and also to be manually oscillatable with respect to the vertical shafts, and gears on said wringer rolls adapted to mesh with either of the vertical shaft gears to change the direction of rotation of the rolls.

3. In a device of the class described, driving means, wringer rolls mounted parallel in a frame 10 and oscillatable about an intermediate horizontal axis, gear means on said respective rolls adapted by oscillation to mesh alternately with said driving means, a handle member pivoted to the top

of said frame, and a tiltable drain board pivoted to the bottom of said frame and connections between said drain board and said frame whereby movement of the handle member will cause a corresponding movement of the drain board.

4. In a device of the class described, wringer rolls, a pair of oppositely disposed feeding fingers, gear means maintaining said fingers in position near the bite of the rolls, means for manually withdrawing said fingers, and means for returning said fingers to feeding position. 10

JOHN B. CASTINO.
